UNITED STATES PATENT OFFICE

160,606

MOTOR BLOCK BENCH

George V. Johnsen, Los Angeles, Calif.

Application September 16, 1947, Serial No. 141,427

Term of patent 3½ years

(Cl. D33—14)

To all whom it may concern:

Be it known that I, George V. Johnsen, a citizen of the United States of America, residing in the city of Los Angeles, in the county of Los Angeles, State of California, have invented a new, original, and ornamental Design for a Motor Block Bench, of which the following is a specification, reference being had to the accompanying drawing, forming a part thereof.

Figure 1 is a perspective view of a motor block bench showing my new design, a motor block being indicated by dot and dash lines for illustrative purposes only;

Fig. 2 is a side elevational view of the same showing my new design;

Fig. 3 is a top plan view of the bench; and

Fig. 4 is an elevational view of the end of the bench taken at 4 in Fig. 1.

The characteristic features of my design reside in the portion shown in solid outline.

I claim:

The ornamental design for a motor block bench, substantially as shown and described.

GEORGE V. JOHNSEN.
